UNITED STATES PATENT OFFICE.

DUANE H. CHURCH, OF NEWTON, MASSACHUSETTS.

DESIGN FOR A BALANCE-STAFF.

SPECIFICATION forming part of Design No. 29,820, dated December 20, 1898.

Application filed November 12, 1898. Serial No. 696,301. Term of patent 14 years.

To all whom it may concern:

Be it known that I, DUANE H. CHURCH, of Newton, in the county of Middlesex and State of Massachusetts, have invented and produced a certain new and original Design for Balance-Staffs, of which the following is a specification, reference being had to the accompanying drawings, forming a part thereof.

This invention relates to a new and original design for balance-staffs; and it consists in the novel features of shape and configuration hereinafter fully described and claimed, and clearly illustrated upon the drawings.

Figure 1 represents a front view of a balance-staff embodying my design. Fig. 2 represents a longitudinal section through the staff.

As shown upon the drawings, the leading or material feature of the design consists of a cylindrical body having two rounded exten-

sions smaller in cross-diameter, one of which tapers outwardly.

a represents the cylindrical body, and *b* *c* represent the extensions. The extension *b* tapers inwardly from its end, and the extension *c* tapers outwardly to its end, the said ends being tapered or converging, as at *d d*.
25

In general the staff presents the appearance of two frustums inserted in the ends of a cylinder whose cross-diameter is greater than 30 theirs.

I claim—

The design for a balance-staff, substantially as shown and described.

In testimony whereof I have affixed my signature in presence of two witnesses.
